GRADING MACHINE

Wilbur L. MacKenzie, Beverly, Mass., assignor to
 United Shoe Machinery Corporation, Flemington, N. J., a corporation of New Jersey

Application July 4, 1944, Serial No. 543,451

27 Claims. (Cl. 33—23)

1

This invention relates to machines having a tool arranged to operate progressively on a work piece in accordance with a predetermined pattern and more particularly to an automatic grading machine. The term "grading" as used herein is understood to apply to an operation in which a reproduction of an article is made which is like as to shape but varies systematically along one or more axes.

An object of the invention is to provide an improved grading machine in which relative movements between a model and its follower are automatically effected and are communicated with predetermined modifications to a tool and a work piece being treated by the tool. To this end, and in accordance with a feature of the invention, a model carrier and a work support are concomitantly given combined movements of rotation and translation during which a follower held in engagement with the periphery of the model controls, through a pantographic mechanism, movements of the tool relatively to the work, there being grading mechanism arranged to modify the movements of the tool independently lengthwise and widthwise of the work.

Another object of the invention is to provide an improved length-grading mechanism. To this end and in accordance with a further feature of the invention an additional lengthwise movement is superposed on the model when the length of the work piece to be operated upon or reproduced is to be different from that of the model. The extent of the length grading is controlled by varying the extent of this additional lengthwise movement of the model carrier.

In accordance with a further feature of the invention, means are provided for automatically adjusting the width-grading and length-grading mechanisms in accordance with the size of a work piece to be operated upon or in accordance with the size of a templet which may be mounted on the work support. Feelers are arranged for engagement with selected portions of the periphery of the work piece or templet to measure the length and width thereof and means operated by these feelers adjust the length-grading and width-grading mechanisms respectively.

The above and other features of the invention, including various novel combinations or parts and details of construction will now be described in

5 detail by reference to the accompanying drawings and pointed out in the claims.

In the drawings,

Fig. 1 is a plan view of one form of apparatus constructed in accordance with the present invention;

Fig. 2 is a section on the line II—II of Fig. 1;

Fig. 3 is a front elevation of the machine shown in Fig. 1;

Fig. 4 is a plan view partly in section along the line IV—IV of Fig. 3;

Fig. 5 is a section on the line V—V of Fig. 1;

Fig. 6 is a section on the line VI—VI of Fig. 5;

Fig. 7 is a section along the line VII—VII of Fig. 5;

Fig. 8 is a section along the line VIII—VIII of Fig. 1;

Fig. 9 is a section along the line IX—IX of Fig. 8;

Fig. 10 is a left end elevation of the machine;

Fig. 11 is a plan view of a portion of the machine on a larger scale than Fig. 1, certain of the parts being removed in order more clearly to illustrate other parts;

Fig. 12 is a section on the line XII—XII of Fig. 11;

Fig. 13 is a section along the line XIII—XIII of Fig. 12;

Fig. 14 is a section along the line XIV—XIV of Fig. 11;

Fig. 15 is a section on the line XV—XV of Fig. 11;

Fig. 16 is a section along the line XVI—XVI of Fig. 11;

Fig. 17 is a section along the line XVII—XVII of Fig. 11;

Fig. 18 is a section along the line XVIII—XVIII of Fig. 11;

Figs. 19 to 21 are plan views of the model carrier and associated mechanism with parts thereof broken away and illustrating the positions of the parts at different points in the cycle of operation when the length-grading mechanism is adjusted to duplicate the exact length of the model;

Fig. 22 is a plan view of the model carrier and associated mechanism illustrating the parts adjusted for maximum down grading of the length of the model;

Fig. 23 is a plan view of a work piece on the

work support showing the action of a cutter on the work;

Fig. 24 is a plan view of a model and a work piece reproduced with the exact length and width of the model;

Fig. 25 is a plan view of the model and work piece, illustrating the movement of the model during the length-grading operation and showing the work piece reproduced in a shorter length in accordance with the extent of movement of the model; and

Figs. 26 and 27 are plan views of the model and work piece illustrating the action of the width-grading mechanism, the parts being positioned in Fig. 26 so that no width grading takes place whereas in Fig. 27 the work piece is graded down in width from the model.

The illustrated mechanism is provided with a tool 10 in the form of a rotary cutter driven by a motor 11 and this tool is arranged to operate upon a piece of work such as a sheet of plywood 13 (Fig. 23) supported on a work support or carrier 12 and, as herein illustrated, held thereon by split friction pegs 15 surrounded by small islands 17 to raise the work above the support 12 and give freedom of action by the cutter. It will be understood that other operations may be performed by providing supports for other kinds of work and other forms of tools, without departing from the invention. Illustrative of these alternatives are such things as the rough-rounding of a sole, the roughing of the margin of a sole or of the overlasted margin upon the bottom of a shoe, and the application of cement to the marginal portion of the bottom of a shoe. In the latter case, the tool would consist of an applying member which might take the form of a nozzle. The arrangement herein shown is such that movement is imparted to both the work and the tool so that there is a relative traversing movement which carries the tool around the periphery of the work and causes the tool to cut according to a pattern graded from a model 14 in the form of a sheet template.

As herein illustrated, the work support 12 is mounted upon a shaft 16 (Fig. 10) rotatable within a hollow bearing which is supported in vertical position on one end of a carrier arm 18 the other end of which is pivoted on an upright post 20 secured in a frame 22. The free end of the arm 18 is turned down to rest on a wear plate 19 (Fig. 1) which supports the arm for lateral swinging movements. Another upright post 24 (Fig. 5) is supported in the frame 22 and on it there is a sleeve 26 forming a bearing for a large gear 28 to which there is keyed a sprocket wheel 30. This sprocket wheel 30 is connected by means of a chain 32 to a similar sprocket 34 attached to a large gear 36 (Figs. 1 and 4) rotatable about the post 20. Another carrier arm 38 (Figs. 4 and 5) swings on the sleeve 26 above the sprocket wheel 30 and has a depending end 40 which slides on a wear plate 42 as the carrier arm is oscillated. The free end of the carrier arm 38 is connected to the free end of the carrier arm 18 by means of a rod 44. In the free end of this carrier arm 38 is journaled a shaft 46 (Figs. 4 and 5) on the lower end of which there is attached a pinion 48 meshing with the large gear 28. Similarly, the work support shaft 16 in the carrier arm 18 is provided at its lower end with a pinion 50 which meshes with the large gear 36.

It is desired to provide the model 14 and the work 13 with a combined motion of rotation and

oscillation such that the point of contact between the tool and the work, for example, does not change in position over a great distance. To get this combined motion there is provided a pinion 52 (Fig. 4) which meshes with the large gear 28 and which is rotatable upon a fixed stud 54 secured to the frame 22. This pinion is provided with an upright pin 56 (Fig. 5) entering a slot 58 in a link 60 which is pivoted to the carrier arm 38 at 62 and at its other end to a link 64 capable of oscillating about a screw 66 carried by the base of the machine. Power to cause this motion is supplied to the machine through a crank 68 having a worm-and-gear connection 69 (Fig. 3) to an upright shaft 70 on which there is a gear 72 meshing with the large gear 28. As a consequence, when the gear 28 is turned, the model, and along with it the work table, are turned through a half revolution to cause the tool to treat the heel end, for example, and are then translated by the action of the crank stud 56 which oscillates the carriers 38 and 18 so that the treatment is carried along the side of the work. This is followed by another half rotation as the toe end is treated and then by another oscillation as the other side of the work is treated. It will be understood that the pinion 52 is turned through two revolutions in moving the model completely around back to its starting position.

A link 110 (Fig. 1) is provided, so that the movements of the tool 10 are governed by a model follower, in the form of a roll 74 (Fig. 5) resting against the periphery of the model 14. This roll 74, the diameter of which is equal to that of the tool, is carried on the end of a bent lever 76 attached to a block 78 (Fig. 2) rotatable about an upright pivot 80. The pivot 80 is carried at the outer end of an arm 82 capable of swinging about a fixed stud 84 which is fixed in a bracket 86 extending rearwardly from the frame 22. From the tool 10 extends a bent link 90 attached to a block 89 (Figs. 1 and 3) which is joined by a pin 91 to an arm 92 which swings about a fixed stud 94 carried by another bracket 96 (Figs. 1 and 10) extending rearwardly from the frame. Sleeved on these same studs 84 and 94 are bell cranks 98 and 100 (Fig. 1) joined by a rod 102, the crank 98 being connected by a link 104 to a pivot 108 substantially above the model follower 74 and the crank 100 being connected by a link 106 to the tool 10, these links being joined by a cross rod 118.

It will be seen, therefore, that the pivot 108 and the tool 10 are joined by a pantographic linkage so that their movements exactly correspond. The pivot 108, however, has a variable relation to the model follower 74 as a result of grading mechanism to be described. Furthermore, to maintain a constant relative speed of movement of the follower and the model at all times during the operation of the machine there is provision for moving the upright stud 80 upon which the arm 76 carrying the follower 74 is pivoted. This stud 80 is surrounded by the forked end of a lever 112 (Figs. 1, 4 and 22) which is pivoted to the frame on a screw pin 114 and has a cam roll 116 resting against the periphery of a cam 118 carried by the shaft 70 and held there by means of a spring 120 (Fig. 1) attached to the outer end of the lever 112 and to a sub-frame 122. The end of the spring is provided with a thumb screw 124 to permit adjustment of its tension. The cam 118 is so shaped that the follower is oscillated at predetermined times during the operation of the machine so that a prede-

terminated portion of the periphery of the model is traversed per unit of time at all portions of the periphery of the model. It should also be noted that the follower 74 is held against the model 14 by means of a spring 126 extending between the sub-frame 122 and an arm 128 attached to the block 78 on which the follower arm 76 is mounted.

Length grading is effected by moving the model 14 axially, i. e., along a line joining the tip end of the toe and the tip end of the heel as it is turned. The model 14 is secured to posts 130 (Fig. 5) carried by a slide 132 (Figs. 5, 11 and 15) which is mounted in a slideway 134 secured to the enlarged upper end 135 (Fig. 5) of the shaft 46. Attached to the slideway is a forwardly projecting arm 136 carrying a stud 137 which forms a support for a pivotally mounted block 138 (Figs. 5 and 16) forming part of a lever having a rearwardly extending arm 139 (Figs. 11 and 16) and an arm 140 provided with a curved slot 141. Adjustable along the slot of this arm is one end of a link 142 which is connected by means of a screw 144 to the far end of the slide 132. A stop 143 is adjustably connected by a screw 145 to the arm 140 to limit the extent of movement of the link 142 away from the stud 137. Accordingly, when the lever 138, 140 is rocked the amount of movement of the slide 132 depends upon the position of the link 142 with respect to the arm 140 and the slotted arm 140 is connected to the link 142 by means of a shiftable pivot pin 146 (Figs. 16 and 17). This pin has a flat enlargement 148 on its lower end the top surface of which is corrugated, as shown in Figs. 17 and 18, to correspond with corrugations 150 on the under side of the slotted arm 140. The pin 146 slides vertically in an upwardly extending guide 147 integral with the link 142 and is normally held upwardly with the enlargement 148 in engagement with the corrugations 150 by means of a flat spring 152 which is forked to engage the shoulder of a reduced flattened portion 154 of the pin. Disengagement of the pivot pin 146 when it is desired to change the point of connection between the slotted arm 140 and the link 142 is effected by a two-armed lever 158, 160 (Figs. 5, 11 and 16) pivoted in the end of the link 142. This lever has the arm 158 overlying the head of the pin 146 and a depending arm 160 (Fig. 5) which is alined with a push rod 162 carried in depending guides 164 formed on the link 142. The push rod normally bears lightly against the depending arm 160 of the lever by reason of a spring 166 which is interposed between one of the guide arms 164 and a block 168 which is secured to the rod with its upper side portion resting against the edge of the link 142. The actuation of this rod 162 for setting the position of the pivot pin 146 will be later described.

To swing the lever 138, 139 and 140, the machine is provided with a cam 170 (Fig. 5) rotatable on a sleeve surrounding the upright shaft 46 and keyed to a small gear 172 which meshes with a large gear 174. The latter is rotatable on the stud 24 and is provided with an arm 176 (Fig. 1) having a cam roll 178 which is held against a cam 180 by means of a spring 182 (Fig. 19). The tension of this spring may be adjusted by means of a thumb screw 184 outside the sub-frame 122. The cam 180 is mounted to rotate with the power-operated shaft 70 thereby operating the cam 170 through the arm 176 and gears 174, 172. The lever arm 139 has a roll 186 which is held against the cam 170 by a spring 188 (Fig.

11). It will be seen, therefore, that the model 14 on the slide 132 may be moved lengthwise during its movement relatively to the follower to an extent which depends upon the setting of the link 142 with respect to the slotted arm 140. With the link 142 positioned on the arm 140 so that its connection to the arm coincides with the pivot of the lever 138, 139 and 140, no lengthwise movement of the model takes place as the lever is swung by the action of the cam 180, but if the link is adjusted along the arm 140 away from the pivot, the model moves lengthwise as it rotates. The movement of the model lengthwise of its slideway 134 depends upon the shape of the cam 180 (Figs. 19 and 21) as the latter is rotated with the shaft 70. In Figs. 19, 20 and 21 there is no length grading because of the fact that the link 142 is positioned parallel to the slideway 134 with its connection to the arm 140 coincident with the pivot of the lever 138, 140, 141, whereas a maximum amount of length grading is introduced with the setting shown in Fig. 22.

Provision is also made for width grading and, to this end, the lever 76 (Fig. 11) which carries the model follower pin 74 is provided with another arm 190 (Fig. 1) which terminates in a ring-shaped portion 192 (Figs. 5, 6 and 22) the center of which is exactly over the follower 74. In this ring-shaped end portion, there is (Fig. 6) a headed sleeve 194 serving as a bearing for a ring-shaped upper end 196 of a U-shaped member 198 retained to turn with the sleeve by a nut 197. The member 198 is integral at its lower end with a grading lever 200 extending lengthwise of the model and pivotally attached by a screw 202 to a slide 204 (Figs. 5, 7 and 8). The slide 204 dovetails in the guideway of a bar 206 which extends lengthwise of the model and is secured to the upper face thereof so that its axis is in alinement with the axis of the model, as determined by a line interconnecting the extreme end of the toe and the extreme end of the heel, as illustrated in Fig. 11 (the bar 206 being omitted from this figure). Secured to this grading lever 200 at an intermediate point by means of a screw 208 passing through a spacing block 209 (Fig. 7) is another grading lever 210 the rear end of which (Fig. 1) swings on the pivot 108 (Fig. 6) which interconnects the link 104 and the cross rod 110. Inasmuch as the movements of the tool 10 correspond exactly to the movements of this pivot 108, the width-grading movement imparted to the pivot 108 is reflected in the action of the tool, and it will be seen, from the continued description, that the extent of this width-grading movement depends upon the position at which the far end of the upper grading lever 210 is connected to, in effect, the slide 204. If the point of connection is above the pivot screw 202 of the lower grading lever 200, then there will be no relative movement between the levers 200 and 210 and no width-grading action. The upper lever 210 is, however, forked to swing about the neck 211 (Figs. 8 and 9) of a pivot block 212 the shank of which is threaded in a latch block 214 adapted to be adjustably connected to the lever 210. The latch block 214 has a striker plate 215 held by screws 217 for a purpose which will later appear. The pivot block 212 is elongated and slides in a groove 216 of a plate 218 which is attached to the slide 204, and this groove 216 is exactly above and parallel to the groove in the slideway 206. The outside faces of the forked end portion of the lever 210 are inclined to fit in a dovetail groove

224 on the under side of the latch block 214, as may be seen from Fig. 9, and the block 216 may be attached to the lever 210 in its adjusted position by means of a latch 226 (Fig. 8) held against serrations in the upper surface of the lever by a spring 228.

Under some circumstances, it may be desired to adjust the grading mechanisms for length and for width in accordance with the dimensions of a sole-shaped templet 240 (Fig. 1), one being provided for each size and width. To facilitate making such adjustments in accordance with the dimensions of one of these templets, for example, the latter is applied to the split pegs 15 on the work table 12, upon which its heel end will occupy a predetermined position regardless of size. The position of the toe end of this templet is ascertained by bringing against it a pin 241 in a toe gage plate 242 (Figs. 1, 10 and 11) hinged to a swinging arm 250. A screw 252 in this arm prevents the hinged plate from dropping below the level of the table 12. The swinging arm 250 is attached to a cross shaft 260 which is carried by hangers 262 and 264 at the far or rear side of the frame 22, but prior to its movement to bring the toe gage into position, a hand latch 256 (Figs. 1, 3 and 5) having a handle 258 and an upstanding end 259 (Fig. 5) is moved to hold the model 14 in its initial position. To accomplish this, the end 259 is brought into engagement with a notch 261 (Figs. 16 and 22) in the side of the lever arm 139.

To set the length-grading mechanism, shaft 260 is provided at its left end with an upright arm 266 having a broadened end portion 268 (Fig. 11) for contact with a block 270 adjustably clamped to a slotted arm 272 which is an extension of the link 142, with the result that the link 142 is swung about its pivotal connection with the slide 132. This movement is permitted by an arrangement which anticipates the actual adjustment of the link 142 by releasing the shiftable pivot pin 146 (Figs. 16 and 17). The release of the pin is effected by moving the rod 162 (Fig. 5) against the arm 160 of the two-armed lever 160, 158 so that the latter will depress the pin against its spring 152 (Figs. 16). To this end, the shaft 260 has yieldably connected to it by means of a friction clutch 274 an upstanding striker 276. The parts of this clutch are pressed together by an axially expandable spring 275. The upper end of this striker is arranged to come in contact with the end of the rod 162 (Figs. 10 and 5) before the arm 266 engages the extension 272 of the link 142. After this length-grading adjustment has been effected, the swinging arm 250 is allowed to fall away from the work, carrying with it the strikers 266 and 276. As this happens, the frictionally connected striker 276 drops against an upright abutment 278 (Fig. 5) which insures the proper angular relation between these two, essential for the correct timing of the movement of the rod 162 to release the pin 146.

Determination of the width-grading adjustment is effected by another portion of this same hand-operated apparatus which comprises a width-measuring lever 280 (Figs. 1, 10 and 11) provided with an abutment 282 positioned to be brought to bear against the ball of the sole-shaped templet 240 at its widest point. The lever 280 is hinged on a bracket 284 on the toe-gage plate 242. At the other end of the lever 280 is an upstanding pin 286 adapted to be received in a slot 288 (Figs. 1 and 14) of an angle piece 290 carried by a flat arm 292 extending rear-

wardly from a pivot block 294. This pivot block surrounds and is carried by a pin 296 which is supported on the frame 22 by a bent bracket 298 (Fig. 3) adjustably secured thereto (Fig. 1). A V-shaped guide member 300 (Fig. 14), having curved entrance flanges 301, is adjustably attached by means of a screw 302 (Figs. 1 and 10) to the angle iron 298 which, in effect, forms an extension of the swinging arm 292. This screw passes through a slot 303 in the overhanging top of the guide member 300 thus furnishing a setting-up adjustment. When the arm 250 on the shaft 260 is raised to bring the toe gage pin 241 into engagement with the templet 240, it will also bring the abutment 282 and its width-measuring lever 280 up for engagement with the ball of the templet 240. As this happens, the rear end of the lever 280 will be guided by the V-shaped slot of the guide member 300 until its pin 286 enters the slot 288. This is followed by manual movement of the lever 280 to bring the ball gage abutment 282 into contact with the templet, which movement will be transmitted from the angle iron 298 through a rod 304 to a bell crank 306 pivoted on the stud 94. The left end of bell crank 306 (Figs. 1 and 3) is adapted to engage the striker plate 215 on the slide block 214, by means of which the upper grading lever 210 is pivotally secured to the upper guide 216 and which is parallel to the dovetail guide in the arm 206, to determine the setting of the block 214 in accordance with the length of the templet 240. The tooth on the latch 226 (Fig. 8) is so shaped that the latch block may be readily moved to the left by a force exerted on the striker plate 215 but the block will be effectively locked in adjusted position and can only be moved to the right upon retraction of the latch.

In the operation of the machine, it will be assumed that the work piece on the support 12 to be operated upon or reproduced is to be smaller both in length and width than that of the model 14. If the bottom of a shoe, for example, is to be roughed or cemented by an appropriate tool substituted for that of the cutter which is illustrated, the shoe will be mounted in a suitable manner on the work support and measurements taken directly from the shoe bottom. In the illustrated embodiment of the machine, a pattern is to be cut from a sheet of material on the work support as indicated in Fig. 23 and accordingly a templet of the desired length and width will first be mounted on the work support 12 on the split pegs 15. Before adjusting the grading mechanisms in accordance with the size of this templet they are first moved manually into initial positions. Thus the arm 142 is adjusted with respect to the curved arm 140 so that its point of connection is directly above the support for the pivotally mounted block 138 (Fig. 16) whereby swinging of the lever 138, 139, 140, during the operation of the machine, will not cause any lengthwise movement of the link 142. In other words, the machine is set for the greatest length. The latch block 214 (Fig. 8) is moved to its rear-most position with respect to the lever 210 in which position the pivot block 212 is spaced rearwardly of the screw 292 or in other words in the position of maximum width grading down from the model. With the templet positioned on the work support 12, the operator swings the toe gage plate 242 upwardly to bring the pin 241 into engagement with the toe end of the templet. During this movement, the striker 276 engages the end of the rod 162 (Fig. 5) thereby

to operate the lever 158, 160, moving the pivot pin 146 downwardly against the force of the spring 152 out of locking engagement with the teeth on the under surface of the curved arm 140. Shortly after this, the arm 266 engages the block 270 thereby to move the arm 272, and with it the link 142, into a position corresponding to the length of the templet. It will be understood that the shorter the templet the greater the distance the forward end of the link 142 is moved along the curved arm 140. During this time the width-measuring lever 280 engages the side of the templet and if the templet is wider than the smallest width to which the machine is capable of grading, the lever is moved in the direction of the arrow (Fig. 1) and operates to swing the left end of the bell crank 306 forwardly to engage the striker plate 215 on the slide block 214 thus moving this forwardly to a position depending upon the width of the templet. The lever 280 is shown in its position just before it reaches its ultimate position opposite to the ball line of the shoe. When the gages are returned to their rearward retracted positions the striker 276 moves away from the rod 162 whereupon the spring 152 locks the length-grading link 142 in its adjusted position. The latch 226 locks the block 214 in whatever position it has been moved by the bell crank 306 so that the width and length-grading mechanisms are now properly set. The templet may now be removed from the work support 12 and a block of plywood or the like may be placed thereon and the machine is ready to reproduce in the work piece a pattern corresponding in shape to that of the model 14 but differing as to length and width in accordance with the size of the templet which has been previously placed thereon.

The machine is now operated by turning the crank 68 although it will be obvious that a suitable motor may be substituted for the crank if desired. First, however, the latch 266 (Fig. 1) is moved to withdraw its upstanding end 288 (Fig. 5) from the notch 261 (Fig. 22) in the lever arm 139. As the crank 68 is turned it operates through the pinions 72, 28, 48 (Fig. 4) to impart a turning movement to the model carrier on the shaft 46 and the shaft is simultaneously translated by reason of the connection of the carrier arm 38 in which the shaft 46 is supported to the link 60 which is oscillated through the medium of the crank pin 56. The resulting motion is illustrated in Figs. 19 to 21 in which the model carrier is first rotated to carry the heel end into the position shown in Fig. 19 after which, by a combined motion of translation and rotation, it assumes the position shown in Fig. 20 whereupon after another turning movement to carry the toe end of the model into the position shown in Fig. 21, the motion of the model is repeated until it comes to rest in the position shown in Fig. 11. During this time it will be apparent that the pinion 52 (Fig. 4) makes two complete revolutions. The connection of the work support 12 on its shaft 16 to the model carrier slideway 134 on its shaft 46, by the mechanism shown in Fig. 4, causes a similar movement to be imparted to the work support. During the movement of the model carrier by the mechanism shown in Fig. 4, an additional lengthwise movement along a line joining the toe and heel ends of the model is imparted thereto. This movement is effected by movement of the cam 170 (Figs. 11 and 19 to 21) operated by its connection to the gear 174 to which is imparted a rocking motion by reason of

its connection to the cam 180, the result being that at predetermined times in the movement of the model carrier the lever 139, 140 is rocked about its pivot thereby causing movement of the link 142 to slide the model carrier as indicated, diagrammatically, in Fig. 25. The extent of this sliding movement depends upon the position of the link 142 with respect to the lever 140, the result being to decrease the effective length of the model as the link is swung to set it farther away from the pivot of said lever.

The tool 10 and the pivot 108 (Fig. 1) which is nearly above the model follower 74, are connected by pantographic mechanism so that the movements of the pivot 108 are duplicated by the tool 10. The pivot 108 is connected to the model follower 74 through the adjustable linkage 210, 200 so that the movements of the pivot 108 will differ from that of the follower in accordance with the distance between the pivot 202 and 211 (Fig. 8) which thereby governs the width grading. If these pivots are in alinement then the pivot 108 will always be in axial alinement with the follower and no width grading takes place. However, with the machine adjusted for width grading, the movement of the pivot 108 will be less than that of the tool so that the tool will grade down from the model as indicated in Fig. 27.

From the above it will be seen that without any effort on the part of the operator in guiding the follower with respect to the model, the machine is capable of grading both as to length and width from a pattern or model and that the adjustments for width and length grading are readily made by means of feelers or gages movable into contact with the periphery of a templet or a work piece upon which an operation is to be performed.

Having thus described my invention, what I claim as new and desire to secure by Letters Patent of the United States is:

1. In combination, a model carrier, a sheet model thereon, a follower, means maintaining said follower in engagement with the periphery of the model, a work support, a tool engageable with a work piece on said support, means for moving said carrier and said support in unison to present successive portions of the periphery 45 of the model to the follower and successive portions of the work piece to the tool, and means connecting said tool and said follower including grading mechanism for modifying the movements of the tool to effect a graded reproduction 50 of said model.

2. In combination, a model carrier, a sheet model thereon, a follower, means maintaining said follower in engagement with the periphery of the model, a work support, a tool engageable 60 with a work piece on said support, means for moving said carrier and said support in unison to present successive portions of the periphery of the model to the follower and successive portions of the work piece to the tool, means including a 65 parallel linkage interconnecting said follower and said tool, and a width-grading mechanism forming part of said last-named means.

3. In combination, a model carrier, a sheet model thereon, a follower, means maintaining 70 said follower in engagement with the periphery of the model, a work support, a tool engageable with a work piece on said support, means for moving said carrier and said support in unison to present successive portions of the periphery of the model to the follower and successive por-

tions of the work piece to the tool, a pantographic mechanism interconnecting said follower and said tool, and means for modifying the movements of the tool to impart a length-grading motion thereto.

4. In combination, a model carrier, a sheet model thereon, a follower, means maintaining said follower in engagement with the periphery of said model, means for turning the carrier to present successive portions of the periphery of the model to said follower, a work support, a tool for operating on a work piece thereon, means for relatively moving said work support and said tool, and means connecting said tool and said follower including grading mechanism for effecting a graded reproduction of said model.

5. In combination, a model carrier, a sheet model thereon, a follower, means maintaining said follower in engagement with the periphery of said model, means for turning the carrier to present successive portions of the periphery of the model to said follower, a work support, a tool for operating on a work piece thereon, means for relatively moving said work support and said tool, means including a parallel linkage mechanism connecting said tool and said follower, a width-grading mechanism forming part of said last-named means, and means for modifying the movements of the tool to impart a length-grading motion thereto.

6. In combination, a model support, a follower, means maintaining said follower in engagement with the periphery of a model mounted on the support, a work support, a tool arranged to act on a work piece mounted on the support, means for moving said supports in unison to present successive portions of the periphery of the model to the follower and successive portions of the work piece to the tool, means connecting the follower and the tool to cause them to move in unison, and means for modifying the movements of one of said supports relatively to the other to cause a grading modification of the movements of the tool.

7. In combination, a model support, a follower, means maintaining said follower in engagement with the periphery of a model mounted on the support, a work support, a tool arranged to act on a work piece mounted on the support, means for moving said supports in unison to present successive portions of the periphery of the model to the follower and successive portions of the work piece to the tool, means connecting the follower and the tool to cause them to move in unison, means for modifying the movements of one of said supports relatively to the other to cause a grading modification of the movements of the tool, and means for adjusting said last-named means.

8. In combination, a model carrier, a follower, means maintaining said follower in engagement with the periphery of a model mounted on the carrier, a work support, a tool arranged to act on a work piece mounted on the support, means for moving said carrier and said support in unison to present successive portions of the periphery of the model to the follower and successive portions of the work piece to the tool, means connecting the follower and the tool to cause them to move in unison, and means for modifying the movements of said carrier relatively to said support to cause a grading modification of the movements of the tool.

9. In combination, a model support, a follower, means maintaining said follower in engagement

with the periphery of a model mounted on the support, a work support, a tool arranged to act on a work piece mounted on the support, means for moving said supports in unison to present successive portions of the periphery of the model to the follower and successive portions of the work piece to the tool, means connecting the follower and the tool to cause them to move in unison, and length-grading mechanism comprising means for modifying the movements of one of said supports relatively to the other.

10. In combination, a model carrier, a follower, means maintaining said follower in engagement with the periphery of a model mounted on the carrier, a work support, a tool arranged to act on a work piece mounted on the support, means for moving said carrier and said support in unison to present successive portions of the periphery of the model to the follower and successive portions of the work piece to the tool, means connecting the follower and the tool to cause them to move in unison including width-grading mechanism, and means for modifying the movements of said carrier relatively to the support to effect a length-grading modification of the movements of the tool.

11. In combination, a model carrier, a follower, means maintaining said follower in engagement with the periphery of a model mounted on the carrier, a work support, a tool arranged to act on a work piece mounted on the support, driving means for rotating and oscillating said work support and carrier in unison, and means including grading mechanism connecting said follower and said tool.

12. In combination, a model support, a follower, means maintaining said follower in engagement with the periphery of a model mounted on the support, a work support, a tool arranged to act on a work piece mounted on the work support, means for imparting rotary movement in unison to said supports, means including pantographic mechanism connecting said follower and said tool, means for imparting an oscillatory movement to one of said supports to obtain a grading action of the tool on the work, and means for adjusting the magnitude of said oscillations.

13. In combination, a model support, a follower, means maintaining said follower in engagement with the periphery of a model mounted on the support, a work support, a tool arranged to act on a work piece mounted on the work support, means for imparting a combined rotary and oscillatory movement in unison to said work supports, means including pantographic mechanism connecting said follower and said tool, and means for varying the oscillatory movement of one of said supports independently of the other to obtain a grading action of the tool on the work.

14. In combination, a model carrier, a follower, means maintaining said follower in engagement with the periphery of a model mounted on the carrier, a work support, a tool arranged to act on a work piece mounted on the support, means for imparting a combined rotary and oscillatory movement in unison to said work support and carrier, means including pantographic mechanism connecting said follower and said tool, and means for imparting an additional variable oscillatory movement to said carrier to obtain a grading action of the tool on the work.

15. In combination, a model support, a follower, means maintaining said follower in engagement with the periphery of a model mounted on the support, a work support, a tool arranged

to act on a work piece mounted on the work support, means for imparting rotary movements in unison to said supports, means including pantographic mechanism connecting said follower and said tool and mechanism for modifying the movements of the tool to obtain a grading action along one dimension of the model, means for imparting oscillatory movements to one of said supports to obtain a grading action of the tool along another dimension of the model, and means for adjusting the magnitude of said oscillations.

16. In combination, a model carrier, a follower, means maintaining said follower in engagement with the periphery of a model mounted on the carrier, a work support, a tool arranged to act on a work piece mounted on the support, means for imparting a combined rotary and oscillatory movement in unison to said work support and said carrier, means including pantographic mechanism connecting said follower and said tool and mechanism for modifying the movements of the tool to obtain a grading action along one dimension of the model, means for additionally oscillating said carrier to obtain a grading action along another dimension of the model, and means for adjusting the magnitude of said oscillations.

17. In combination, a model carrier, a follower, means maintaining said follower in engagement with the periphery of a model mounted on the carrier, a work support, a tool arranged to act on a work piece mounted on the support, means for imparting a combined rotary and oscillatory movement in unison to said work support and said carrier, means including pantographic mechanism connecting said follower and said tool and mechanism for modifying the movements of the tool to obtain a width-grading action thereof, means for oscillating said carrier lengthwise of the model to obtain a length-grading modification of movements of the tool, and means for adjusting the magnitude of said oscillations.

18. In combination, a model carrier, a model mounted thereon, a follower, means maintaining said follower in engagement with the periphery of said model, a work support, a tool arranged for engagement with a work piece on said support, means for relatively moving said model carrier and said follower to present successive portions of the periphery of the model to the follower, means for imparting similar relative movements to the work support and the tool, means including pantographic mechanism connecting said follower and tool to cause them to move in unison, and a grading mechanism interposed in said last-named means for modifying the movements of the tool, said grading mechanism including an adjustable linkage connected to said model and operated by the relative movement between said model and said follower.

19. In combination, a model carrier, a model mounted thereon, a follower, means maintaining said follower in engagement with the periphery of said model, a work support, a tool arranged for engagement with a work piece on said support, means for turning said model carrier and said work support to present successive portions of the periphery of the said model to the follower and successive portions of the work piece to the tool, and means including pantographic mechanism connecting said follower and said tool to cause them to move in unison, said mechanism having a slide mounting interposed between the model carrier and the carrier-turning mechanism.

20. In combination, a model carrier, a model

mounted thereon, a follower, means maintaining said follower in engagement with the periphery of said model, a work support, a tool arranged for engagement with a work piece on said support, means for turning said model carrier and said work support to present successive portions of the periphery of the said model to the follower and successive portions of the work piece to the tool, means including pantographic mechanism connecting said follower and said tool to cause them to move in unison, a width-grading mechanism interposed in said last-named means for modifying the movements of the tool, said width-grading mechanism including an adjustable linkage connected to said model and operated by the relative movement between said model and said follower, and means for sliding the carrier lengthwise of the model carried thereby to effect a length-grading modification of the movements of the tool.

21. In combination, a model carrier, a model mounted thereon, a follower, means maintaining said follower in engagement with the periphery of said model, a work support, a tool arranged for engagement with a work piece on said support, means for imparting a combined rotary and oscillatory movement in unison to said carrier and said work support to present successive portions of the periphery of the model to the follower and successive portions of the work piece to the tool, means including pantographic mechanism interconnecting the follower and the tool to cause them to move in unison, and a grading mechanism interposed in said last-named means for modifying the movements of the tool, said mechanism having a slide mounting interposed between the model carrier and the carrier-turning mechanism, and cam-operated means for sliding the carrier lengthwise of the model carried thereby to effect a length-grading modification of the movements of the tool.

22. In combination, a model carrier, a model mounted thereon, a follower, means maintaining said follower in engagement with the periphery of said model, a work support, a tool arranged for engagement with a work piece on said support, means for imparting a combined rotative and bodily movement to said carrier and said support to cause them to move in unison to present successive portions of the periphery of the model to the follower and successive portions of the work piece to the tool, means including a parallel linkage interconnecting the follower and the tool, and width-grading mechanism comprising a link connecting said tool and a superposed point on said linkage, pivotally connected grading levers connecting said point and said follower, a slide movable axially of the model, and means for pivotally connecting the far ends of said levers to spaced points on said slide whereby the movements of the tool are modified by this width-grading mechanism.

23. In combination, a model carrier, a model mounted thereon, a follower, means maintaining said follower in engagement with the periphery of said model, a work support, a tool arranged for engagement with a work piece on said support, means for imparting a combined rotative and bodily movement to said carrier and said support to cause them to move in unison to present successive portions of the periphery of the model to the follower and successive portions of the work piece to the tool, means including a parallel linkage interconnecting the follower and the tool, and width-grading mechanism compris-

ing a link connecting said tool and a superimposed point on said linkage, pivotally connected grading levers connecting said point and said follower, a slide movable axially of the model, means for pivotally connecting the far ends of said levers to spaced points on said slide whereby the movements of the tool are modified by this width-grading mechanism, and means for adjusting the relative points of connection between the far ends of the levers and said slide to modify the degree of width grading.

24. In combination, a model carrier, a model mounted thereon, a follower, means maintaining said follower in engagement with the periphery of said model, a work support, a tool arranged for engagement with a work piece on said support, means for imparting a combined rotative and bodily movement to said carrier and said support to cause them to move in unison to present successive portions of the periphery of the model to the follower and successive portions of the work piece to the tool, means including a parallel linkage interconnecting the follower and the tool, width-grading mechanism comprising a link connecting said tool and a superposed point on said linkage, pivotally connected grading levers connecting said point and said follower, a slide movable axially of the model, and means for pivotally connecting the far ends of said levers to spaced points on said slide whereby the movements of the tool are modified by this width-grading mechanism, and means for sliding the model carrier axially to effect a length-grading modification of the movements of the tool.

25. In combination, a model carrier, a model mounted thereon, a follower, means maintaining said follower in engagement with the periphery of said model, a work support, a tool arranged for engagement with a work piece on said support, means for imparting a combined rotative and bodily movement to said carrier and said support to cause them to move in unison to present successive portions of the periphery of the model to the follower and successive portions of the work piece to the tool, means including a parallel linkage interconnecting the follower and the tool, width-grading mechanism comprising a link connecting said tool and a superposed point on said linkage, pivotally connected grading levers connecting said point and said follower, a slide movable axially of the model, and means for pivotally connecting the far ends of said levers to spaced points on said slide whereby the move-

ments of the tool are modified by this width-grading mechanism, means for sliding the model carrier axially to effect a length-grading modification of the movements of the tool, and means for adjusting the points of connection between the far ends of the levers on the slide and for adjusting the magnitude of the axial sliding movement of the carrier thereby to effect variations in the degree of width grading and of length grading.

26. In combination, a model carrier, a model thereon, a follower, means maintaining said follower in engagement with the periphery of a model on the carrier, a work support, a tool arranged to act on a work piece on said support, means for relatively moving said carrier and said follower to present successive portions of the periphery of the model to the follower, means for imparting similar relative movement to said work support and tool, grading mechanism between said follower and said tool, and means operated by movement into engagement with the periphery of a member on the work support for adjusting the grading mechanism in accordance with the size of said member.

27. In combination, a model carrier, a model thereon, a follower, means maintaining said follower in engagement with the periphery of a model on the carrier, a work support, a tool arranged to act on a work piece on said support, means for relatively moving said carrier and said follower to present successive portions of the periphery of the model to the follower, means for imparting similar relative movement to said work support and tool, width-grading mechanism between said follower and said tool, means for oscillating the model carrier to impart a length-grading modification of the movements of the tool, and means engageable with spaced points on the periphery of a member on the work support for adjusting said width-grading mechanism and the amplitude of the oscillations of the model carrier in accordance with the width and length of said member.
